Attorney.

UNITED STATES PATENT OFFICE.

FRANK J. KRISTOFER, OF ST. PAUL, MINNESOTA, ASSIGNOR TO BROWN & BIGELOW, OF ST. PAUL, MINNESOTA, A CORPORATION OF MINNESOTA.

TOY GUN.

1,262,060.

Specification of Letters Patent. Patented Apr. 9, 1918.

Application filed May 24, 1917. Serial No. 170,665.

To all whom it may concern:

Be it known that I, FRANK J. KRISTOFER, a citizen of the United States, residing at St. Paul, in the county of Ramsey and State 5 of Minnesota, have invented a new and useful Improvement in Toy Guns, of which the following is a specification.

My invention relates to toy guns in which a harmless device is provided for amusement, being simple in construction and 10 easily operated.

The primary object is in providing a triggerless gun, the gun hammer being released by a slight transverse movement of 15 the hammer.

A further object is in a device which is formed of stamping from thin sheet metal, the different parts of a toy gun.

Another object is in providing a toy 20 which is adapted to shoot paper or other disks and which is harmless to a child or user but still affording a great deal of amusement.

The above objects with other features will 25 be more clearly defined and set forth in the following specification and claims:

In the drawing forming part of this specification:

Figure 1 is a perspective of my gun.

Fig. 2 is a plan view of the gun.

Fig. 3 is a side elevation of the gun, a portion of which is broken away.

Fig. 4 is a front elevation.

Fig. 5 illustrates a detail portion of an 35 alternative construction.

Fig. 6 illustrates a side elevation of the construction illustrated in Fig. 5.

In the drawing, A represents a toy gun having a handle portion B and barrel portion C which are formed of thin sheet metal 40 1, or any other suitable material. The handle B is approximately parallelepiped shaped having side walls 2 and 3 which are bent so as to lie parallel to each other and 45 are connected by the back portion 4. Three sides of the parallelepiped handle B are open. A circular portion 5 is formed on the top of the back 4 and is adapted to close the rear end of the barrel C when the handle 50 is secured to the barrel.

Lugs 6 are formed on the upper portion of the sides 2 and 3 and are adapted to engage in the opening 7 being clenched over in

the barrel C so as to hold the handle B connected to the barrel C. 55

The barrel C is formed of a single piece of material having a lower longitudinal slot 8 which extends the full length on the bottom of the barrel C and an upper short slot 9 extending longitudinally at the rear end 60 of the barrel C. The slot 9 is cut away or widened so as to form a catch 10 at its rear end.

Arms 11 are formed by cutting out a portion of the barrel C and bending the same 65 upward so as to form holding means for a disk or missile D. The upper ends of the arms 11 lie approximately parallel to each other and are so positioned as to hold by a slight friction, the disk or missile D upright 70 between the same.

A hammer 12 having an arm 13 is pivotally secured on the wall 2 of the handle B, by means of an eyelet 14. The eyelet 14 is formed from and is integral with the wall 75 2. The arm 13 is formed with a notch 15 on its lower end in which one end of a coil spring 16 is adapted to engage. The other end of the coil spring 16 being held in the slot 17 formed in the lower portion of the 80 side 4 of the handle B.

The upper end of the arm 13 extends through the slots 8 and 9 and is formed with a head or striking end 18. The head 18 is formed integral and from the same piece of 85 material as the arm 13 by bending the portion 19 of the arm 13 so as to extend at right angles to the same and then bending the enlarged portion 20 back so as to lie adjacent the portion 19, thereby forming a striking 90 head 18 which extends at right angles to the arm 13 and extending on either side of the arm. By this simple construction, a strong striking hammer 12 is formed which is adapted to reciprocate back and forth in 95 the slots 8 and 9. The lower edge 21 of the striking head 18 is adapted to extend below and in front of the arm 13 so that when the hammer 12 is in released or forward position as illustrated in Fig. 3, the edge 21 will 100 engage the upper surface of the barrel C so as to form a stop for the hammer 12 in this position and to prevent the edge of the arm 13 striking the forward end of the slot 9 when the hammer is released. The stop 105 21 also prevents the arm 13 from cutting

the slot 9 during the use of the gun A. The slots 8 and 9 are just a trifle wider than the thickness of the arm 13 so as to allow the arm to reciprocate back and forth in the 5 slots freely.

In use of the gun A, the hammer 12 is cocked or drawn back into engagement with the catch 10 and a paper disk D or other suitable missile is placed between the 10 engaging arms 11 as illustrated in Fig. 1. The gun A is then held in the right hand of the user so as to place the knuckle of the thumb alongside the head 18 forcing it transversely in the slot 9 and releasing the 15 lever 13 from the catch 10 whereupon the spring 16 will automatically force the hammer 12 into the position illustrated in Figs. 2 and 3 and striking the edge of the disk D and shooting it forward from the 20 barrel of the gun. The disk will cut the air and will invariably travel straight ahead for a considerable distance thus affording a good deal of amusement in the use of the gun A.

25 In the construction illustrated in Figs. 5 and 6, the missile holding means is formed by cutting a circular portion out of the barrel C at 22, leaving a small portion of the cut out circular portion attached to the 30 barrel C. The portion cut out is then bent backward and its edges bent upward so as to form engaging wings 23. The engaging wings 23 are adapted to perform the same function as the arms 11 and the portion 35 24 which connects the wings 23 forming a stop for the disk or missile D. A cross section through the wings 23 and stop 24 would be substantially U shaped. The stop 24 thus preventing the disk D from 40 being placed too far back in the holding means so as to be properly discharged from the gun when the hammer 12 is released. By means of the construction illustrated in 45 Figs. 5 and 6, the disk D is always held in the correct position to be discharged.

Any number of disks can be used and the construction of the gun is such that if given 50 the ordinary care, it will operate perfectly without getting out of order for a long period of time. It is obvious that other missiles than the paper disk can be used and that the construction can be varied.

While I have illustrated one particular form of construction of device, I desire to

have it understood that I do not wish to 55 confine myself to this particular form but that the invention can be carried out by other means and applied to uses other than those above set forth within the scope of the following claims:—

60 I claim

1. In a toy gun formed from thin sheet metal having a tubular barrel portion, a parallelepiped shaped handle portion, a longitudinal slot formed along the bottom of said barrel, a longitudinal slot extending centrally along a portion of the top, a catch formed in said top slot, a spring secured to one end of said hammer and a 65 striking head formed on the other end of said hammer and engaging means formed on said barrel ahead of the forward end of said top slot for holding a disk shaped missile whereby, when said hammer is released from said catch, said spring will force said striking head into engagement with said missile to shoot the same.

2. In a device of the class described, a triggerless gun formed from thin sheet material, a tubular hollow barrel portion, means formed on said barrel for holding a missile, a handle secured to said barrel, a striking hammer pivoted to said handle, slots formed in said barrel in which said hammer is adapted to reciprocate, a catch formed in one of said slots and a stop formed on said hammer which is adapted to engage the surface of said barrel when said hammer is released from said catch to 90 limit the forward movement of said striking hammer.

3. In a device of the class described, a triggerless gun formed from thin sheet material, a tubular hollow barrel portion, 95 fingers formed integral with and extending upwardly from said barrel for holding a missile, a handle secured to said barrel, a striking hammer pivoted to said handle, slots formed in said barrel in which said hammer is adapted to reciprocate, a catch formed in one of said slots and means formed on said hammer which is adapted to engage the surface of said barrel when said hammer is released from said catch to prevent 100 said hammer from striking the forward end of the slot in which it reciprocates.

105 FRANK J. KRISTOFEK.
